CLAPBOARD-SAWING MACHINE.

1,184,043.

Specification of Letters Patent.

Patented May 23, 1916.

Original application filed January 2, 1914, Serial No. 809,891. Divided and this application filed July 31, 1914. Serial No. 854,300.

To all whom it may concern:

Be it known that I, MILo LEONARD STEARNS, a subject of the King of Great Britain, and resident of L'Orignal, Province of Ontario, Dominion of Canada, have invented certain new and useful Improvements in Clapboard-Sawing Machines, of which the following is the specification.

This invention relates to improvements in 10 clap-board sawing machines, and the objects of the invention are to eliminate the jarring effect usual to the log supporting members as the saw is engaged in cutting the log, to simplify the construction, and 15 other objects which will be made clear hereafter; and it consists essentially of the improved construction of machine particularly described and set forth in the following specification and accompanying drawings forming part of the same.

In the drawings, Figure 1 is a side elevation of the clapboard sawing machine showing the improved device attached thereto. Fig. 2 is a plan of the same. Fig. 3 is an 20 end elevation. Fig. 4 is a detail of the supporting bracket for the log.

In the drawings like characters of reference refer to like parts in the several drawings.

30 The mechanism of this machine is in general similar to that set forth in application Serial Number 809,891, from which the present application has been divided.

Referring to the drawings; A⁹ is the 35 reciprocating carriage which is adapted to carry the log and feed it in a longitudinal direction to the band saw S. This carriage is of suitable construction and mounted on the framework B by means of the rollers 10 40 which engage tracks 11 on the framework, the carriage being reciprocated by any suitable means. The band saw S is double edged and preferably operates vertically. The supporting means for the log are adapted 45 to engage the ends thereof near the periphery and turn the log about its vertical axis. This is accomplished by means of a pair of crank members C and D, each of which is axially movable and has a portion 50 13 journaled in suitable bearings 14 on the carriage. The opposite arm 15 of each crank member has its end adapted to be connected to a log near the periphery by means of the chuck members 16 which are driven through

the end of the log and have sockets shaped 55 to engage the ends of the crank members C and D.

The crank members C and D are arranged to be moved in an axial direction to engage with the chuck members 16, and to this end 60 the lever A is pivotally attached to the quadrant A², the motion being transmitted through the rods A³ and A⁴ attached to the lever A equidistant to and on opposite sides of the lever fulcrum. The opposite ends of 65 the rods A³ and A⁴ are pivotally attached to the crank members A⁵ and A⁶ mounted intermediate of the shafts A⁷ and A⁸, the ends of which shafts remote from the cranks A⁵ and A⁶ carry the striking levers A⁹ and 70 A¹⁰ which are designed to fit the collars A¹¹ and A¹² attached to the end 13 of the crank members C and D.

The logs are adapted to be turned a distance at each reciprocation of the carriage 75 in order that a new cut may be taken, the mechanism by which this is accomplished being in all respects the same as that set forth in application Serial Number 809,891. It will be quite clear that the motion of the 80 log will be somewhat of an eccentric nature owing to the manner of supporting the same from a point near its periphery and due to the arms 15 being offset from the crank members C and D. At the instant when the 85 saw S engages with the log and during the sawing of the same the lever G supports the log, this being accomplished by means of the shaft G' provided with a fixed lever G² carrying the balance weight G³. The shaft 90 G' is supported by suitable bearings G⁴ and G⁵. The brackets G⁶ are fixed to the shaft G' and carry the pawls G⁷. The lever G is pivotally attached intermediate of its ends to the machine by means of the shaft G⁹, 95 the end far remote from this shaft having a downwardly extending curved rack G⁸ rigidly fixed thereto. The lever G is supported intermediate of its length by the arm G¹⁰ rigidly attached to the outer end of the lever G¹¹ operated by the shaft G⁹. When 100 the saw is about to engage the log, the weight G³ is disengaged from the inclined plate G¹³ causing the shaft G' to be rotated through a short distance, the movement of 105 the shaft being governed by the lever G¹⁴ which in turn is connected to the strap G¹⁵. As the rotation of the log takes place it will

be quite clear that the lever G is depressed at the front side, the back end being elevated and the pawls G⁷ due to the movement of the shaft G' engage with the teeth 5 of the curved rack G⁸. As the saw S reaches the end of the log the weight G³ engages with the corresponding inclined plate G¹⁸ and releases the pawl G⁷ thereby allowing the lever G to take up its original 10 position. The shock or jar on the arms G¹⁰ is counterbalanced by the action of the spiral springs G¹⁶ operating on the lever G⁴⁷ which is rigidly attached to the shaft G⁹. It will be clear that the function of the 15 lever G is to relieve the crank members C and D from any undue strain which may be placed upon them during the operation of the sawing of the log.

As many changes could be made in the 20 above construction and many apparently widely different embodiments of my invention, within the scope of the claims, constructed without departing from the spirit or scope thereof, it is intended that all matter contained in the accompanying specification and drawings shall be interpreted as 25 illustrative and not in a limiting sense.

What I claim as my invention is:

1. A mechanism for the purpose specified 30 comprising a reciprocatory carriage, axially movable crank members thereon having their ends adapted to engage the ends of the log near the periphery thereof, levers pivotally mounted intermediate of their ends, adapted to engage with said log, a downwardly disposed curved rack rigidly mounted on the said levers, pawls adapted to engage with the said rack and means for actuating the said pawls, as and for the 40 purpose specified.

2. A mechanism for the purpose specified comprising a reciprocatory carriage, axially movable crank members thereon having their ends adapted to engage the ends of the 45 log near the periphery thereof, levers pivotally mounted intermediate of their ends adapted to support the said log, downwardly disposed curved racks mounted on the said levers, a shaft, brackets mounted on 50 the said shaft, pawls mounted on the said brackets, a counterbalance weight designed to be attached to the said shaft, and tapered plates designed to engage with the said counterbalance weight, as and for the 55 purpose specified.

3. A mechanism for the purpose specified

comprising a reciprocatory carriage, axially movable crank members thereon having their ends adapted to engage with the ends of the log near the periphery thereof, a 60 shaft, levers pivotally mounted intermediate of their ends to the said shaft, such levers being designed to engage at one end with the said log, downwardly disposed curved racks mounted in the opposite ends of the 65 said levers, pawls adapted to engage with the said racks, means for operating the said pawls, levers rigidly attached at one end to the said shaft, arms mounted on the outer ends of the said levers and resilient means 70 for eliminating the shock of sawing from the last said levers and arms, as and for the purpose specified.

4. A mechanism for the purpose specified 75 comprising a reciprocatory carriage, axially movable crank members thereon, adapted to engage the ends of a log near the periphery thereof, levers pivotally mounted intermediate of their ends for supporting the log to relieve the crank members during the sawing 80 operation, a gravity controlled shaft and a co-acting action between said shaft and said levers whereby said shaft controls the action of the said levers.

5. A mechanism for the purpose specified 85 comprising a reciprocatory carriage, axially movable crank members thereon adapted to engage the ends of a log near the periphery thereof, levers pivotally mounted intermediate of their ends for supporting the log 90 to relieve the crank members during the sawing operation, a gravity controlled shaft and a co-acting action between said shaft and said levers whereby said shaft controls the action of the said levers, said connection 95 including cam means.

6. A mechanism for the purpose specified 100 comprising a reciprocatory carriage, axially movable crank members thereon adapted to engage the ends of a log near the periphery thereof, levers pivotally mounted intermediate of their ends for supporting the log 105 to relieve the crank members during the sawing operation, and automatic means for limiting the pivotal motion of the said levers.

In witness whereof I have hereunto set my hand in the presence of two witnesses.

MILO LEONARD STEARNS.
